Robert Wilde

United States Patent Office.

ROBERT WILDE, OF PHILADELPHIA, PENNSYLVANIA.

Letters Patent No. 79,172, dated June 23, 1868.

IMPROVEMENT IN STEAM-GENERATORS.

The Schedule referred to in these Letters Patent and making part of the same.

TO ALL WHOM IT MAY CONCERN:

Be it known that I, ROBERT WILDE, of the city of Philadelphia, in the State of Pennsylvania, have invented a new and useful Improvement in Steam-Boilers or Generators; and I do hereby declare that the following is a full, clear, and exact description of the construction and operation of the same, reference being had to the accompanying drawings, making a part of this specification, in which—

Figure 1 is a transverse section of a connected pair of the said improved boilers or steam-generators, on the dotted line *v w* of fig. 2, and

Figure 2 a longitudinal section of the same, on the dotted line *x y* of fig. 1—

Like letters of reference indicating the same parts when in both figures.

My improvement relates to those flattened steam-boilers or generators which have the upper and lower sides of their shells stayed to each other by close vertical longitudinal partition-plates of iron, so as to divide their respective interiors into several long, distinct, uncommunicating steam-generating chambers.

And my invention consists in perforating the said partition-plates with numerous holes, as hereinafter described, for the purpose of allowing the contained water and steam free communication with all the different divisions.

My invention also consists in the application to steam-boilers or generators, having the perforated vertical longitudinal partition-plates described, of vertical transverse partition-plates across the divisions produced by the said longitudinal partition-plates, substantially as hereinafter described, for the purpose of preventing any injurious surging of the contained water of the boiler or generator, when the same is subjected to a longitudinal or pitching motion, as in a steamer or other carrier.

My invention also consists in the application to said boilers, arranged with one directly above another, as hereinafter described, of vertical overflow-pipes, for the purpose of affording an open communication and equality of pressure in the said different boilers, and also for the purpose of allowing the water to be fed to the lower boiler, by overflows from the upper one, substantially in the manner hereinafter described.

And, finally, my invention also consists, in combination with said boilers, arranged with one directly above another, and connected together by means of the said vertical overflow-pipes, in the employment of a float in the lower boiler, in connection with a feeding-cylinder on the upper boiler, arranged to operate together in the manner hereinafter described, for the purpose of feeding the said boilers automatically.

Referring to the drawings, A A and B B are sections of two of the improved boilers, arranged with one above the other, and leaving a suitable return-flue space, F, between them, *a' a'* and *b' b'* being the upper and the lower portions of the respective shells of the said boilers, *a'' a''* and *b'' b''* the respective perforated longitudinal partition-plates, and *a''' a'''* and *b''' b'''* the respective transverse partition-plates; C, the rotary feeding-cylinder within a suitable case, D; E, the water-supply pipe; G G, the overflow-pipes, and I, the float in the lower boiler B B.

The exterior shells of the boilers A and B consist of a series of plates, of boiler-iron, bent and riveted together so as to produce a long, flattened boiler, with convex ends, tied together by the perforated vertical longitudinal partition-plates *a'' b''*, so as to produce a series of long, distinct chambers, communicating with each other through the said perforations in the partitions *a'' b''*, substantially as represented in the drawings. Each of the said chambers is divided, by the vertical transverse partition-plates *a''' b'''*, into separate compartments, the said partition-plates *a''' b'''* being only about half the height of the respective boilers in which they are fixed, substantially as represented in the drawings.

The said boilers A and B are arranged so that the one, A, will be directly above the other, B, leaving a return-flue, F, between them, and are connected together by means of the open overflow-pipes G G.

These pipes G G are each secured in a vertical position through the respective shells of the boilers A and B, the lower end of each pipe opening fully into the lower boiler, B, without projecting downward into the same, and the upper end of each projecting upward into the upper boiler, A, and opening into the same at the intended water-line, or at about half the height of the boiler A, substantially as represented in the drawings.

The two boilers, A and B, are intended to be "walled in" in any suitable manner, so as to afford a fire-space or furnace under the front end of the lower boiler, B, with a direct flue extending back therefrom, and up behind the rear end of the said boiler into the return-flue F, between the two boilers A and B, the latter flue continuing upward in front and back over the upper surface of boiler A, to the usual escape-flue or chimney, the exposed parts of the overflow-pipes G G, and upper surfaces of the boilers A and B being, of course, protected from any injurious action of the flames by a covering of fire-brick or any suitable bad conductor of heat.

The float I is a large, hollow, air-tight sphere of thin metal, which has a rigid stem, i', that will slide easily through any suitable packing-box, i'', fixed on the upper side of the lower boiler, B, so as to allow the said ball to float, or rise and fall with the surface of the water contained in the said boiler.

The feeding-cylinder C is a hollow vessel, having an opening, c', through one of its sides, and is fixed concentrically upon a shaft, c'', so that it can be rotated thereby in a corresponding case, D, which is fixed upon the upper side of the upper boiler, A, substantially as shown in the drawings.

The lower side of the said case D communicates with the boiler A, through an opening, d', in both, and its upper side communicates with the water-supply pipe E, through a like opening, and which corresponds with the opening c' in the rotary cylinder C. Between the outer side of the cylinder C and the inner side of its containing-case D, there is applied a suitable packing, c''', for the purpose of producing a steam-tight joint between them. The cylinder-shaft c'' extends forward to a short distance over the front end of the boiler A, and has thereat a fast pulley, H, and a loose pulley, H', whereby alternate rotary motion and rest can be given to the cylinder C, by means of a suitable band operated by any independent motive-power, not necessary to be shown in the drawings.

Attached to the lower boiler, B, there is a bent lever, k, which has its fulcrum at k', and its power-end jointed to the projecting upper end of the stem i' of the float I, whilst its weight-end extends upward in front of the upper boiler, A, and forms a loop, h'', beside the pulleys H H', and through this loop h'' the required "band" is intended to pass alternately to the said pulleys H H'.

The lever K is arranged in its relation to the float I and pulleys H H', so that when the contained water of the boiler B is at its proper height, or water-line, the float I will hold the loop h'' directly opposite to the side of the loose pulley H', and thus allow the motion of the "band" to continue without rotating the cylinder C, and so that when the water shall fall any considerable distance below its proper line in the boiler, the float I, falling with it, will cause the loop-end of the said lever K to be brought over to the position shown in the drawings, thus shifting the band to the fast pulley H, which latter, being rotated thereby, will give rotary motion to the feeding-cylinder C.

A steam-boiler or generator, constructed in the flattened form and strengthened by staying the upper and lower portions of the shell together by close, vertical partition-plates, which divide it into a horizontal series of separate longitudinal steam-generating apartments, as heretofore, will require less material in its construction, and be stronger than if the same number of chambers of equal capacity were produced by so many separate cylindrical boilers; and hence the said flattened form of construction described has peculiar advantages over the old separate cylindrical boilers arranged side by side; but, as there has not heretofore been any provision made to equalize the height of the water in the different apartments of such flattened boiler, it has not been brought into general use.

It will be seen that, in the operation of my herein-described improvement, the said longitudinal partition plates a'' or b'', being each perforated with numerous small holes, the required uniformity in the depth of the water, as well as in the pressure of the steam in the different apartments, will be attained, and in the most simple manner; and, also, that when the boiler is subjected to a transversely-oscillating motion, as from the rolling of a sea-steamer, the surging of the contained water will be sufficiently prevented without interfering with or varying the required uniformity in the pressure of the steam throughout all the different longitudinal apartments or divisions.

It will also be seen that while the transverse partition-plates a''' or b''' divide each of the said longitudinal apartments of the boiler into several separate apartments, each corresponding in height with the intended height of the water-line of the boiler, as shown and described, the surging of the contained water when the boiler is subjected to a longitudinally-oscillating motion, as from the pitching motion of a steamer in a rough sea, will be sufficiently prevented by the said transverse partition-plates, and this without preventing free access of any one to the different apartments, when desired, for the purpose of repairs or cleaning.

When two of the said boilers A and B, constructed as described, are arranged with the one above the other, with a return-flue between, as shown in the drawings, they will be connected together, so as virtually to produce a single steam-generator, by means of the overflow-pipes G G, because the said pipes will constantly serve as means of open communication between the upper and the lower portions of the said generator, and it will, therefore, be seen that as the upper ends of the said pipes G G extend upward no further than to the intended water-line of the upper boiler A, and downward no further than to pass through the shell of the upper portion only of the lower boiler B, as shown in the drawings, and being open at both ends, and the intended water-line of the said lower boiler B never being higher than the transverse partition-plates b''' b'', the said pipes G G will always remain open, and consequently allow the pressure of the steam to be at all times alike in both A and B.

It will also be seen that as the float I will rise and fall in accordance with the rise and fall of the surface of the water in the lower boiler B—the proper water-line being about the height of the transverse partition-plates b''' b'', and the float, lever, and pulleys being relatively adjusted for the purpose—the lever K will be caused to shift the "running band" (before mentioned, but not shown,) from one to the other of the pulleys H H', and thus give alternate motion and rest to the feeding-cylinder C; and that said feeding-cylinder, when being rotated, will, at each rotation, receive from the supply-pipe E feed-water equal to its capacity, and dis-

charge the same into the upper boiler A; and that, therefore, when the water in the lower boiler becomes reduced considerably below its proper water-line, the float I, following, and consequently acting upon, the lever K, will shift the said running band from the loose pulley H' to the fast pulley H, and thus cause the said cylinder C to rotate, and thereby discharge water into the boiler A, as stated, until by overflowing and falling through the pipes G G, a sufficient quantity of water reaches the lower boiler B to raise the surface of the same therein to its proper water-line, and, at the same time, to cause the float I to move the lever K, so as to shift the band from the fast pulley H to the loose pulley H', and thus stop the feeding-motion of the cylinder C.

As the shell of a flattened steam-boiler or generator has before been constructed in the form and manner described, and the boiler divided longitudinally into separate, uncommunicating steam-generating apartments, by means of close, vertical tie-partitions, I wish it to be understood that I do not consider myself to be the first inventor of such flattened, many-chambered boilers or generators; but having fully described my improvement,

What I claim as new of my invention, and desire to secure by Letters Patent, is confined to the following, viz:

1. I claim, in a steam-boiler or generator, the perforated dividing partition-plates a'' or b'' , substantially as and for the purpose described.
2. In combination with a steam-boiler or generator, the vertical transverse partition-plates a''' or b''' , the same being constructed and arranged substantially as and for the purpose described.
3. I claim the vertical overflow-pipes G G, constructed and arranged substantially as and for the purpose described.
4. In combination with two or more steam-boilers or generators A and B, arranged with one directly above another, and connected together by means of the open vertical overflow-pipes G G, as described, the employment of the float I in the lower boiler, and the feeding-cylinder C, with its case D, on the upper boiler, the same being connected together by the lever K, pulleys H H', and any suitable moving "band," and the whole being arranged to operate together, substantially as and for the purpose described.

ROBERT WILDE.
